APPARATUS FOR PRINTING NEWSPAPERS
AND THE LIKEWilliam Ward Davidson, Evanston, Ill., assignor,
by mesne assignments, to Davidson Corpora-
tion, a corporation of Illinois

Application May 16, 1947, Serial No. 748,393

5 Claims. (Cl. 270—18)

1

My present invention relates to an improvement in apparatus for making or producing newspapers or pamphlets and the like.

In the printing of newspapers it is mainly the present practice to use printing presses of the web type. Such presses are extremely costly to install and operate and are only economically feasible for the printing of newspapers of substantial circulation or of substantial numbers of pamphlets or catalogues. The cost of such equipment is prohibitive, for example, for the printing of newspapers in communities of small population and having a limited circulation. As a further example similar cost factors are involved in the publishing of short runs of catalogues or pamphlets which cannot be economically produced with the web type of presses.

In recent years the art of offset printing has been advanced so that highly satisfactory printed sheets may be quickly and economically produced. In certain of my prior patents, of which Patent No. 2,387,750, dated October 30, 1946, is typical, I have disclosed a printing press for the offset printing of one side of a sheet. The machine of my above patent comprises in its essentials two cylinders one being twice the diameter of the other and with the larger of the two cylinders being provided with a plate segment and platen or impression segment and with the smaller cylinder being provided with a common form of rubber offset blanket. Suitable dampening and inking mechanisms are arranged with respect to the cylinder of large diameter to effect the dampening and inking of the printing plate carried by the plate segment in the revolution of this cylinder. During a half revolution of the larger cylinder when the plate carried by the plate segment is in engagement with the blanket of the smaller cylinder the inked image on the plate is transferred to the blanket on the small cylinder, which since it is of half the diameter of the large cylinder makes a complete revolution for the above one half revolution of the larger cylinder. A sheet to be printed is then inserted between the printing couple formed by the two cylinders so that the sheet in passing between the latter during the succeeding half revolution of the larger cylinder is disposed between the platen or impression segment of the latter cylinder and the blanket cylinder to effect the printing of the side of the sheet in contact with the blanket during the following full revolution thereafter of the small diameter cylinder.

The machine as above described is not com-

2

pletely satisfactory for the purposes of my present invention since it is only capable of printing one side of a sheet which of course is not suitable for newspaper work although in some instances it would serve for certain kinds of pamphlets or catalogues. The aforesaid elements of the above machine however, with the addition of a second large diameter cylinder may, however, be readily adapted to provide a perfecting offset printing press.

An arrangement of two large diameter cylinders and one small diameter cylinder to accomplish perfecting offset printing of a sheet is known and is broadly disclosed in Patent No. 1,423,165, dated July 18, 1922, to Stern. However, while the arrangement of the several cylinders and inking and dampening means of this patent is highly unsatisfactory for purposes of my present invention the principle by which 20 perfector offset printing may be accomplished is disclosed.

Briefly perfector offset printing by such an assembly of three cylinders, namely two large cylinders of the same diameter and one small cylinder of half the diameter of the large cylinders may be accomplished by the substitution of a blanket segment carrying a suitable blanket, such as a rubber or the like for the platen or impression segment of the first or large diameter cylinder of the machine of my above patent. In the preferred arrangement of parts of the printing machine for purposes of my present invention the first large diameter cylinder is preferably disposed above the small diameter blanket cylinder and with the second large diameter cylinder being disposed generally above the first large diameter cylinder. This second large diameter cylinder comprises a plate segment for carrying a suitable printing plate. In the aforesaid arrangement of cylinders it will be observed that the first large diameter cylinder, that is the cylinder intermediate the small diameter cylinder and the other large diameter cylinder, comprises a plate segment carrying a printing plate and a blanket segment carrying a suitable blanket. The small diameter cylinder, as before, carries a suitable blanket and the second or other large diameter cylinder is provided with a plate segment for carrying a suitable plate. Preferably individual dampening and inking means are associated with each of the larger cylinders for the dampening and inking of the printing plates carried by the plate segments thereof. As before, during the half revolution 45 of the first large diameter cylinder when the

printing plate carried thereby is in engagement with the blanket of the small diameter cylinder the ink image of the printing plate is transferred to the blanket. Also, during the aforesaid half revolution of the first large diameter cylinder the plate carried by the plate segment of the second large diameter cylinder is in engagement with the blanket carried by the blanket segment of the first large diameter cylinder so that the ink image of such printing plate is transferred to the blanket on the first large diameter cylinder. A sheet to be printed on both sides is then fed between the printing couple formed by the first large diameter cylinder and the small diameter cylinder whereby in the following half revolution of the first large diameter cylinder and the full revolution of the small diameter cylinder the blankets carried by the cylinders last referred to are in register and effect the simultaneous printing of opposite sides of the sheet passing therebetween of the ink images on the pair of blankets. During the printing of a sheet, the second large diameter cylinder is rotated a half revolution with the plate carried thereby being dampened and inked by the dampening and inking mechanism associated therewith preparatory to the next transfer of the inked image to the blanket of the first large diameter cylinder. As disclosed hereinafter single dampening and inking means operative to dampen and ink both plates of the two large diameter cylinders may be provided although such an arrangement is preferable for use only if the amount of printed matter on both sides of the sheet is of a small amount.

The construction of a perfecting offset printing machine of the above character may for all practical purposes conform to my above referred to patent with that machine being modified to incorporate the second large diameter cylinder in the manner noted. In the machine of the patent referred to there is provided a chain delivery mechanism for carrying a sheet to be printed between the printing couple and to deliver the sheet optionally with either side disposed upwardly. Such a construction is preferable for purposes of my instant invention for reasons to be noted in the detail description of a preferred embodiment of my present invention. It is to be noted that although the printing press above described is continuously driven that the printed sheets will be delivered by the machine at spaced intervals or intermittently which function of the machine will hereinafter appear is utilized in the making or producing of newspapers, pamphlets or catalogues and the like.

I have conceived that a newspaper or the like may be readily printed and assembled by providing a plurality of perfecting offset printing presses such as of the character above noted arranged in lengthwise aligned relation with respect to a conveyor and upon which conveyor each of the printing machines discharges a printed sheet, and with the movement of the conveyor being related to delivery of the printed sheets from the several printing machines so that newspapers comprising one printed sheet from each printing machine are collated on the conveyor.

It is therefore an object of my present invention to provide apparatus for making newspapers or the like embodying means for simultaneously printing successive pluralities of sheets and depositing the successive pluralities of printed sheets in a row at predetermined intervals and

during the intervals between the deposit of successive pluralities of sheets means of advancing the row a predetermined distance.

More specifically it is an object of my invention to provide apparatus as aforesaid in which the row of printed sheets is advanced during the intervals between the delivery of successive pluralities of printed sheets to collect at the end of the row toward which it is advanced successive groups in which each group consists of one sheet from each plurality of printed sheets arranged in superposed relation.

The mode of operation of the above described offset printing press lends itself to the accomplishment of the aforesaid objects in that while the machine operates continuously printed sheets are delivered intermittently in predetermined timed sequence due to the aforescribed rotation of the cylinders in the transferring of the inked images from the plates to the blankets and of the printing of the sheets by the passage thereof between the printing couple when the pair of blankets are in register. Thus in such a printing press a printed sheet is delivered thereby followed by an interval before the next printed sheet is delivered although the machine operates or runs continuously. During this interval the conveyor upon which the sheet printed by the first machine is disposed may be caused to be advanced to a second perfecting machine which is operated synchronously with or on the same cycle as the first press to be in position to receive the sheet printed by the second press in superposed relation with the sheet on the conveyor delivered by the first printing press. Any desired number of such perfecting printing presses may be arranged in series lengthwise of the conveyor with the several printing presses operating on the same cycle of operation to provide during the time the printing machines are each printing a sheet for advancement of the conveyor so that the several machines except for the first machine deliver a printed sheet in superposed relation upon sheets already collected by the intermittent advancement of the conveyor from the preceding printing press or presses. The first printing press always delivers a printed sheet directly onto the conveyor with the operation of the other printing machines and conveyor being such that each succeeding printing press delivers a sheet in superposed relation with respect to the sheet delivered by the preceding printing press.

The complete newspaper is delivered at the end of the conveyor adjacent the last printing machine. It will be understood that the perfecting printing presses are designed to print the desired size of sheets and may for example be adapted to print a sheet which when subsequently centrally folded forms four pages of a newspaper. The perfecting offset presses of my present invention may for example be designed to produce newspapers of small size of the order of present forms of small tabloid types of newspapers.

It is a further object of my invention to provide apparatus as aforesaid in which the pluralities of printed sheets each comprise a plurality of pages and including means of folding each group of the collected sheets to form a serial arrangement of pages of a newspaper or the like.

In accomplishing this object and assuming a twelve page newspaper is to be printed the apparatus may comprise three printing machines of

5

a character in which each printed sheet comprises four pages and with the printing presses being arranged with respect to the conveyor to be collected in groups of three sheets, one from each of the presses. I propose to embody in the apparatus a suitable folding mechanism to fold the groups of sheets centrally as they are collected at the end of the conveyor to form a twelve page newspaper.

From the foregoing it will be readily understood that any desired number of printing machines for printing sheets comprising the desired number of pages may be provided together with an appropriate interconnection of cycle of operation of the presses and the conveyor to effect the reproduction of newspapers or the like of any desired number of pages.

The above and other objects and advantages of my present invention will appear from the detail description of a preferred embodiment of my invention.

Now in order to acquaint those skilled in the art with the manner of constructing and utilizing an apparatus embodying the principles of my present invention, I shall describe in connection with the accompanying drawings a preferred embodiment of the apparatus of my invention.

In the drawings:

Figure 1 is a side elevational view of an apparatus constructed in accordance with my present invention;

Figure 2 is an end elevational view of the right hand end of the apparatus of Figure 1 partly broken away to illustrate in elevation a portion of the driving mechanism for the conveyor of the apparatus of my invention;

Figure 3 illustrates a plurality of printed sheets, for example, three sheets, as in the embodiment chosen for purposes of disclosing my invention, with each side of the sheets having two pages printed thereon, disposed in a row, which forms a step of the method of my invention, and which number of printed sheets the printing presses of the apparatus of Figures 1 and 2 and are adapted to print and deliver successively at predetermined intervals;

Figure 4 illustrates the manner in which a plurality of printed sheets, for example, three sheets, with both sides of each sheet having two pages printed thereon, are adapted to be grouped in superposed relation by the apparatus of my invention and which grouping of the sheets comprises a further step of the method of my instant invention; and

Figure 5 illustrates a collected group of sheets of Figure 4 folded centrally along the dotted lines thereof to form a twelve page newspaper or the like.

Referring now to the drawings I have shown in Figures 1 and 2 an apparatus constructed in accordance with my invention comprising a conveyor 6 supported at a convenient height above the floor by a plurality of legs 7 forming in part a supporting framework for the apparatus and above which conveyor a plurality of perfecting offset presses 8, 9, and 10, are disposed and suitably supported. The presses 8, 9, and 10 are all of like construction and in the main may be of the construction shown in my above referred to patent with the exception of the provision of the additional cylinder previously referred to and to be hereinafter described in greater detail. It will be understood that while I have shown three printing presses, that any desired number

6

of presses may be provided depending upon the number of sheets or pages of which the newspaper or the like is to consist.

The illustration of the printing presses 8, 9, and 10 is largely diagrammatic it being believed that from the disclosure of my above referred to patent, and the further following description of adapting the machine disclosed in that patent for perfecting offset printing that the manner in which satisfactory machines may be constructed will be readily apparent to those skilled in the art without describing in detail all the specific structural elements of the presses.

It will be observed in Figures 1 and 2 that an electric motor 12, carried by a suitable supporting platform 13, is provided adjacent one end of the apparatus providing a source of motive power for driving the apparatus. The armature shaft 14 of the motor has a pulley 15 fixed thereto and about which and a pulley 16 carried at the outer end of the lengthwise horizontally extending drive shaft 17 for the press 8 a drive belt 18 is trained for effecting rotation of the latter shaft and pulley. The shaft 17 has connection by means of any suitable known form of flexible coupling 19 with a shaft 19 intermediate the presses 8 and 9, which shaft 19 in turn by means of a flexible coupling 20 has connection with drive shaft 22 for the printing press 9. A flexible coupling 23 provides for connection of drive shaft 22 with an intermediate drive shaft 24 extending between the presses 9 and 10 and with the latter shaft having connection by means of the flexible coupling 25 with a drive shaft 26 for the printing press 10. The several above referred to shafts are arranged in substantially aligned relation lengthwise of the conveyor and provide for the substantial simultaneous operation of the several presses 8, 9, and 10. Each of the drive shafts 17, 22, and 26 has a gear 27 suitably keyed thereto. The gears 27 associated one with each of presses 8, 9, and 10 by the interconnection of the several above described shafts are adapted to be driven conjointly with the gear 27 of each press functioning in the same manner in each machine in view of which the description hereinafter will be limited in the main to the press 8.

It will be seen that the gear 27 of printing press 8 has meshing engagement with a blanket cylinder gear 28 which has suitable connection with the blanket cylinder 29 for effecting rotation of the latter. The gear 28 as shown has meshing engagement with the gear 31 which has connection with a shaft carrying a first plate and platen cylinder 33. The gear 31 has meshing engagement with a gear 34, with the gear 34 being keyed or otherwise secured to a shaft carrying a second plate cylinder disposed above and in juxtaposition of the first plate and platen cylinder 33.

A chain delivery mechanism for conveying sheets to be printed through the presses and delivering the printed sheets upon the conveyor 6, as diagrammatically shown in Figure 2 comprises a chain means 37 trained about gear means associated with the blanket cylinder 29 and lower ejector wheel means 39. The chain means 37 is driven by the rotation of the blanket cylinder 29 and if desired reference may be had to my aforementioned patent for a detail description of a specific structure suitable for this purpose. As disclosed in that patent the chains of the chain delivery mechanism 37 are provided with one or more jaws or clamps 40 which are adapted to grasp the leading edge of a sheet to

be printed by the machine for drawing the sheet through the printing couple formed by the cylinder 29 and the cylinder 33. As viewed in Figure 2 of the drawings the chain means travels in a counterclockwise direction so that when the jaw means 40 carried thereby is disposed in position to receive a sheet for drawing the same through the printing couple the jaw means is closed by any suitable mechanism to draw the sheet to the left between the printing couple as viewed in Figure 2. When the jaw means reaches the position shown in Figure 2 it is adapted to be opened by any suitable cam or other trip mechanism for depositing the printed sheet upon the conveyor 6 which as will be clear from Figure 2 is disposed immediately below the ejector wheel means 39 of chain delivery mechanism 37. The sheets to be printed are caused to be fed by any suitable feeding mechanism between the printing couple formed by the cylinders 29 and 33 from the right hand side of the machine as viewed in Figure 2 and as indicated by the arrow 42. As previously indicated the blanket cylinder 29 is provided with a rubber or other type of transfer blanket of any suitable and known character. These blankets are removably secured to the blanket cylinder by appropriate clamping devices as is well known in the art. The blanket cylinder 29 in the embodiment of my invention herein disclosed is preferably of half the diameter of the plate and platen cylinder 33 with the latter cylinder being provided as shown diagrammatically in Figure 2 with a plate segment 45 and a blanket segment 46 which as is known are adapted to be removably secured to the cylinder 33. The plate carried by the plate segment 45 embodies the printed matter to be reproduced on one side of sheets passed through the printing couple formed by the cylinders 29 and 33. The cylinder 35 is preferably of the same diameter of the cylinder 33 and in the embodiment of the invention herein disclosed it comprises or has associated therewith a second plate segment carrying any suitable known form of printing plate as indicated at 47. A suitable dampening means 49 is arranged with respect to the cylinder 33 for effecting dampening of the printing plate carried by segment 45 thereof and further of a suitable inking mechanism 50 for effecting inking of the plate subsequent to dampening thereof in the clockwise rotation of cylinder 33. Similarly, the cylinder 35 has associated therewith dampening means 52 of conventional construction, and an ink fountain means 53 for effecting successive dampening and inking of the plate 47 upon the counterclockwise rotation of cylinder 35.

As shown the cylinder 35 and the dampening and inking means 52 and 53 respectively are carried in a suitable frame 55 which is adapted to be detachably mounted at the upper end of the press by means of hinged connection at 56 and clamping means 57 for securing the unit including the cylinder 35 in position disposed above the cylinder 33. The clamping means 57 may comprise any suitable form of eccentric clamping device for holding the unit 55 rigidly in position shown in Figure 2 and against an adjustable abutment 58 carried by the frame 59 provided for the support of the cylinders 33 and 29 and the inking and dampening mechanisms 50 and 49, respectively, together with the chain delivery mechanism and the driving instrumentalities previously referred to generally.

Preferably the blanket cylinder 29 and the cylinders 33 and 35 are of suitable dimensions for effecting the printing of two pages of printed

matter on both sides of a sheet of suitable dimension fed between the printing couple of the press with of course the printing plates carried by the plate segments of the cylinders 33 and 35 providing for effecting of the printing of two pages on each side of a sheet fed to the machine. In the arrangement of a small diameter blanket cylinder 29 and the two large diameter cylinders 33 and 35 as described it will be observed that the plate carried by the plate segment 45 is first caused to be dampened by the dampening means 49 and then inked by the inking means 50 during a half revolution of this cylinder the inked image on the plate carried by the plate segment 45 is transferred to the blanket of blanket cylinder 29. The several cylinders 29, 33 and 35 are so arranged with respect to each other and driven by the aforescribed gear means so that the plate carried by the plate segment 47 of the cylinder 35 is caused to be dampened by the dampening means 52 and then inked by the ink fountain means 53 with the rotation of the cylinder 35 being such with respect to the cylinder 33 so that the plate carried by the plate segment 47 is adapted to transfer its image to the blanket carried by blanket segment 46 of the cylinder 33. Upon effecting of the transfer of the inked image from the plate carried by the plate segment 45 to the blanket of the blanket cylinder 29, and transfer of the inked image from the plate 47 of cylinder 35 to the blanket 46 of cylinder 33 a sheet is caused to be fed between the printing couple formed by the blanket of cylinder 29 and the blanket of the blanket segment cylinder 33 and upon a full revolution of cylinder 29 with the blanket of segment 46 in register with the blanket carried by cylinder 29 printing of both sides of a sheet passing between the pair of blankets is effected simultaneously. With this arrangement of the several cylinders with respect to each other a single sheet having two printed pages on each side thereof is adapted to be delivered by the delivery mechanism 37 and disposed upon the conveyor 6 of the apparatus. If desired the dampening means 49 and inking means 50 may be eliminated in which event the cylinder 35 would be provided with a segment 51 carrying a rubber inking pad opposite the plate segment 47 thereof and in such modification the printing plate carried by cylinder 33 will necessarily need to be a rubber plate, electrotype or other like form of plate rather than an offset lithographic plate. However, as previously indicated the latter arrangement probably would only be suitable when the amount of printed matter on the sheet is small.

Assuming that it is desired to produce a twelve page newspaper, the plate segment 45 of press 8 will be provided with an appropriate plate for the printing of pages 2 and 11 of the newspaper, and the plate 47 will be of a character for the printing of pages 1 and 12 of the newspaper. In press 9 the cylinder 33 thereof will be provided with a plate for effecting the printing of pages 4 and 9 of the newspaper, and the cylinder 35 thereof will be provided with a printing plate to effect the printing of pages 3 and 10 of the paper. In press 10 the printing plate carried by cylinder 33 thereof will be of a character for reproducing pages 6 and 7 of the paper and the plate carried by the cylinder 35 will be for effecting reproduction of pages 5 and 8 of the paper. As previously related the presses 8, 9 and 10 are all operated substantially synchronously so that as a sheet is fed between the printing couple of each machine

after transfer of the inked images from the several plates to the blankets of the cylinders 33 and of the blanket cylinders 29 for each of the presses, the presses will substantially simultaneously each print and deliver a printed sheet bearing the pages aforesaid and deposit them in longitudinal alignment in a row upon the conveyor 6. When the apparatus is set into operation the motor 12 through the driving means above described effects continuous driving of the several presses 8, 9 and 10 so that they are adapted to deliver successive pluralities of printed sheets as described.

As illustrated in Figure 4 one of each of the sheets delivered by the several presses are collected in superposed relation and upon a group of sheets being collected as illustrated in this figure the group may be centrally folded along the dotted lines thereof as indicated to form a twelve page newspaper or pamphlet with the pages in series as illustrated in Figure 5.

In order to effect the collecting or collating in superposed relation of successive groups of sheets each comprising one sheet from each of the printing presses 8, 9 and 10, I propose to provide for the intermittent advancement of the conveyor 6 or of the row of printed sheets during the intervals between the delivery of successive pluralities of sheets from the several printing machines. The conveyor or row of previously printed sheets is advanced during each of the aforesaid intervals to the next succeeding printing station to have a sheet from the next succeeding printing press disposed above the sheet or sheets advanced from the preceding printing press or presses.

Referring again to Figures 1 and 2 it will be observed that a sprocket wheel 60 is connected at the end of the drive shaft 17 for the printing press 8 adjacent the coupling member 18 and about which sprocket 60 and a sprocket 62 disposed below the conveyor 6 a drive chain 63 is trained. The sprocket 62 is connected or keyed to one end of a horizontally extending shaft 65, which shaft 65 adjacent its other end is supported in a bracket 67 and carries a bevel gear 66. The bracket 67 is formed as part of a support structure 63 for supporting a gear mechanism providing an intermittent drive for the conveyor 6. The bevel gear has meshing engagement with a bevel gear 69 carried by a shaft 70 and which shaft 70 carries a suitable disc or plate 71 to which one end of a link 73 is pivotally connected as at 74 with the other end of the link having pivotal connection as at 75 with a reciprocating sector member 76. The sector 76 has meshing engagement with a pinion 77 including a one way clutch mechanism carried by the shaft 78. The shaft 78 carries a sprocket 80 about which and a sprocket wheel 82 fixed to a shaft 83 extending transversely of the conveyor 6, a suitable drive chain 85 is trained for effecting rotation of the shaft 83. The shaft 83 is journaled in suitable bearing members 86-86, with the shaft intermediate its ends carrying a driving sprocket 87 for the conveyor 6. An endless chain 88 is chained about the drive sprocket 87 and an idler sprocket 90 disposed at the forward or delivery end of the apparatus.

The drive arrangement last described is such that the sector 76 is adapted to be driven in a clockwise direction as viewed in Figure 1 to effect rotation the clutch pinion 77 with the pinion 77 upon such clockwise rotation of a sector 76 effecting rotation of shaft 83 carrying the drive sprocket 87 of the conveyor to drive the

conveyor chain in a counterclockwise direction as viewed in Figure 1. After the sector reaches its limit of travel or rotation in the clockwise direction the sector is rotated by means of the connecting link 73 in a counter-clockwise direction with the overrunning clutch of the pinion 77 upon this movement of the sector permitting return movement of the same without reversing the direction of travel of the conveyor chain 88. It will be observed that with the continuous driving of the drive shaft 17 for the press 8 that the conveyor chain 88 of the conveyors means 6 is caused to be intermittently advanced a predetermined amount as determined by the ratio of the gearing mechanism last described. The relation of the drive mechanisms for driving the several presses 8, 9, and 10, by means of the drive shafts 17, 22, and 26 thereof, respectively, together with the driving mechanism for the intermittent advancement of the conveyor chain 88 is such that after the depositing of a plurality of sheets in a row by the several presses upon the conveyor as by means of the gripper jaw means 40 of the chain delivery mechanisms 37 of each of the machines, and before the delivery of the following successive plurality of printed sheets one by each of the printing machine 8, 9, and 10, the conveyor is advanced so that the preceding sheet delivered by the press 8 is disposed below the delivery chain means of the press 9, and the preceding sheet printed by the press 9 is disposed below the chain delivery means of the press 10 to have disposed thereon in superposed relation a printed sheet from each of the printing presses 9 and 10, respectively. The intermittent advancement of the conveyor chain 88 when a plurality of printing presses such as the presses 8, 9 and 10 are disposed in lengthwise alignment above the conveyor 88 is such that the printed sheets are advanced a distance equal to the lengthwise spacing between a pair of the printed sheets and the lengthwise dimension of a sheet in the row so that, for example, after the delivery of a successive plurality of printed sheets by the several presses in a row upon the conveyor the conveyor chain is advanced so that the sheet delivered by the press 8 upon the conveyor is disposed in a position below the press 9 to have the next succeeding sheet delivered thereby in superposed relation over the printed sheet delivered by the press 8, and likewise in that advancement the sheet printed by the press 9 is disposed in a position to have the following sheet printed by the press 10 disposed thereon in superposed relation. In the initial starting up of the apparatus three successive printing operations of each of the machines will be required before a completed newspaper is delivered at the delivery end of the machine. It will be observed that thereafter in the operation of the apparatus that the printing press 8 always delivers a printed sheet upon the conveyor and that the printing press 9 delivers a printed sheet in superposed relation upon the previously printed sheet delivered by the printing press 8, and that the printing press 10 delivers a sheet in superposed relation upon the conveyor upon a sheet printed in the previous printing operation by the press 9 which is superposed upon a sheet printed by the press 8 in the printing operation immediately previous thereto so that a group of sheets comprising one printed sheet from each of the printing presses 8, 9, and 10 are collated in superposed relation in the order

shown in the typical example referred to and as illustrated in Figure 4 below the printing press 10.

It will be observed that the presses 8, 9 and 10 are caused to be continuously operated with the several cylinders of each thereof effecting the simultaneous printing of both sides of a sheet and the intermittent delivery of the sheets upon the conveyor 6 in a lengthwise row and with the row being advanced in timed relation to the intermittent delivery of the several printing machines to provide at the end printing machine of a collected group of sheets consisting of one printed sheet from each of the several printing presses. The conveyor means 6 preferably comprises a pair of spaced lengthwise extending angle iron members 92 and 93 between which the sheets are disposed by the chain delivery mechanism and with the conveyor chain being provided with appropriately spaced fingers 95 for engaging the sheets to advance them successively from press to press to be in position to have a sheet from each of the printing presses disposed in superposed relation upon the sheets deposited upon the conveyor from a preceding press or presses.

In the practice of my present invention when a newspaper or the like is for example to be composed of twelve pages as in the embodiment herein chosen for the purposes of disclosing my invention it is desirable to provide mechanism for effecting folding of a collected group of sheets as shown in Figure 4 along the dotted lines as previously described to provide a serial arrangement of the successive pages. To accomplish folding of such a group of sheets as shown in Figure 4, I propose to provide any conventional form of folding mechanism such as indicated at 100 at the delivery end of the apparatus so that in the stepped advancement of the conveyor 88 of the conveyor means 6 the collected group of sheets beneath the press 10 is delivered to a folding table 102 supported by the legs 103 adjacent the delivery end of the conveyor. Upon the delivery of a collected group of sheets upon the folding table 102 the folding of the sheets may be synchronized with the delivery of the collected group of sheets to the folding table by folding mechanism operating off of a cam 105, fixed to the shaft 106 supporting the cylinder 33 of the printing press 10. A roller or cam follower 106 is carried at the upper end of arm 107 which arm is pivoted intermediate its ends in a bracket 108 fixed to the side panel or frame member 109 of the press 10 and to the lower end of which arm 107 a link 108 is pivotally connected as at 109. The link 108 has pivotal connection at its other end with one end of a lever 110 fixed to a rotatable shaft 111 extending transversely of the folding table 102. A transversely extending folding knife 113 is fixed to shaft 111 and upon rotation of the latter the folding knife is adapted to effect folding or creasing of the group of sheets along the dotted lines thereof as illustrated in Figure 4 and positioning the group of sheets between a pair of folding rollers 115-115. The folded group of sheets may then be conveyed by a conveyor 116 to the delivery end of the apparatus at which the completed newspapers may be gathered or carried away by further conveyor means (not shown) to a loading platform or the like. It will be obvious of course that the conveyor 116 may be connected with any suitable driving means for driving the same or if desired the conveyor may be driven by means of the electric motor 12.

While I have shown what I consider to be the

preferred embodiment of my invention it will be understood that various modifications and rearrangements may be made therein without departing from the spirit and scope of my invention.

I claim:

1. In an apparatus of the character described, a plurality of printing presses arranged in uniform spaced relation in a lengthwise row, each of said printing presses including a printing couple adapted when continuously rotated to print and deliver intermittently successive sheets, drive means associated with said presses for continuously driving the printing couples thereof in synchronism thereby to provide for the printing and intermittent delivery of successive pluralities of printed sheets in a lengthwise row at uniform intervals, a conveyor arranged in juxtaposition lengthwise of said printing presses for receiving the successive pluralities of printed sheets from said printing presses, and drive means associated with said conveyor and including means operatively associating it for operation in predetermined time sequence with said first drive means for advancing said conveyor intermittently in successive steps from press to press during the intervals between the delivery of successive pluralities of printed sheets from said printing presses, whereby said conveyor is in a stationary position during the delivery thereto of successive pluralities of said sheets by said presses so that stacks of superposed sheets, one from each of said presses, are adapted to be delivered intermittently at the end of the conveyor toward which it is advanced.

2. In an apparatus for making newspapers and the like, the combination of a conveyor, a plurality of printing presses arranged in a row in uniform spaced relation lengthwise of said conveyor, said presses each having a printing couple disposed directly above said conveyor and including printing cylinders adapted upon rotation thereof for printing successive sheets at predetermined uniform intervals, sheet delivery means rotatable with one of the printing cylinders for each of said printing couples for delivering sheets printed thereby directly upon said conveyor, drive means for said presses for driving the same continuously and in synchronism, and said drive means including means associated with said conveyor for intermittently advancing the same in the intervals between the successive printing of sheets by the printing presses a predetermined amount to receive in superposed succession one printed sheet from each printing press.

3. In an apparatus for making newspapers and the like, the combination of a conveyor, a plurality of printing presses arranged in a row in uniform spaced relation lengthwise of said conveyor, said presses each having printing cylinders disposed directly above said conveyor and adapted upon the continuous rotation thereof for printing successive sheets at predetermined uniform intervals, sheet delivery means rotatable with one of the printing cylinders for each of said presses and extending generally transversely of said conveyor for delivering the printing sheets from said presses upon said conveyor, drive means for said presses for driving the printing cylinders thereof continuously and in synchronism, and said drive means including means associated with said conveyor for intermittently advancing the same in the intervals between the successive printing of sheets by the presses a predetermined

13

amount to receive in superposed succession one printed sheet from each printing press.

4. In an apparatus for making newspapers and the like, the combination of a conveyor, a plurality of printing presses arranged in a row in uniform spaced relation lengthwise of said conveyor, said presses each having perfecting printing means including printing cylinders disposed directly above said conveyor and adapted on rotation thereof for printing a plurality of pages on successive sheets at predetermined timed intervals, sheet delivery means rotatable with a printing cylinder of each perfecting printing means for each of said presses and extending generally transversely of said conveyor for delivering the printed sheets from said presses upon said conveyor, drive means for said presses for driving the printing cylinders thereof continuously and in synchronism, and said drive means including means associated with said conveyor for intermittently advancing the same in the intervals between the successive printing of sheets by said printing presses a predetermined amount to receive in superposed succession one printed sheet from each printing press.

5. The apparatus of claim 4 characterized by

the provision of folding means, and means associated with the printing press at the delivery end of the conveyor and said folding means for driving the latter in timed sequence with respect to said conveyor for folding the collected group of sheets at the delivery end of said conveyor on a line extending between the printed pages of the sheets.

WILLIAM WARD DAVIDSON.
